UNITED STATES PATENT OFFICE.

DE ESCOTT GREEN, OF HUNTINGTON, WEST VIRGINIA.

DESIGN FOR A DECORATIVE MOLDING.

Application filed September 29, 1928. Serial No. 28,322. Term of patent 7 years.

To all whom it may concern:

Be it known that I, DE ESCOTT GREEN, a citizen of the United States, residing at Huntington, in the county of Cabell and State of West Virginia, have invented a new, original, and ornamental Design for Decorative Molding, of which the following is a specification, reference being had to the accompanying drawing, forming part thereof.

Figure 1 of the drawing is a front eleva-

tion of a portion of a decorative molding showing my new design; and

Fig. 2 is a cross view of the decorative molding showing my new design taken on the line 2—2 of Fig. 1.

I claim:

The ornamental design for a decorative molding as shown.

DE ESCOTT GREEN.
